UNITED STATES PATENT OFFICE

HENRY DIETRICH, OF PITTSBURG, ASSIGNOR TO GEORGE A. MAIER,
ALLEGHENY CITY, PENNSYLVANIA.

DESIGN FOR A LAMP-CHIMNEY.

SPECIFICATION forming part of Design No. 14,373, dated October 30, 1883.

Application filed August 29, 1883. Term of patent 14 years.

To all whom it may concern:

Be it known that I, HENRY DIETRICH, of Pittsburgh, in the county of Allegheny and State of Pennsylvania, have invented a new and original Design for Lamp-Chimneys; and I do hereby declare the following to be a full, clear, and exact description thereof.

My design relates to the top of lamp-chimneys and similar articles, its purpose being to form an ornamental finish to the top of lamp-chimneys above the edge thereof. Heretofore these lamp-chimneys have been blown to shape, and the top or mouth of the chimney formed contracted or straight, or flared out, as desired; and in some cases, after the top has been flared by means of suitable tools, the top has been crimped, the edge being pressed down by a series of knives, so as to form crimps or indentations therein.

The object of my design is to form an ornamentation for the top of the chimney; and it consists, essentially, in a lamp-chimney having a circular edge, and a beading or similar ornamentation raised above the said edge.

In the drawings, Figure 1 is a side view of my design, and Fig. 2 is a top view thereof. The chimney *a* is blown to shape and finished by suitable tools, and has the mouth *b*, which is flared, and the circular edge *c*, to give it a neat appearance. Raised above the circular edge *c* is the beading ornamentation *d*. This beading consists of a series of globular

beads around the edge of the chimney, globular beading giving a fine finish to the chimney, and giving a finish which allows the top of the chimney to be of the same height around its entire edge; beading is raised or extends up above the chimney, leaving the edge so the bead. The top of the chimney presents to the eye the regular flared edge of the ordinary plain chimney, and the beading or like ornamentation around thus combining the effect of the plain finished chimney with the fancied top.

What I claim, and desire to protect by Letters Patent, is—

1. The design for lamp-chimney as shown and described, consisting in a circular top or edge, and a beading or similar ornamentation raised above said edge.

2. The design for lamp-chimney as shown and described, consisting in a mouth having a circular top or edge, and a beading or similar ornamentation raised above said edge.

In testimony whereof I, the inventor, HENRY DIETRICH, have hereunto set my hand,

HENRY DIE
